UNITED STATES PATENT OFFICE.

CHRISTIAN P. PAULSEN, OF SEATTLE, WASHINGTON.

HEEL FOR BOOTS AND SHOES.

Application filed November 28, 1922. Serial No. 603,788.

To all whom it may concern:

Be it known that I, CHRISTIAN P. PAULSEN, a citizen of the United States, resident of Seattle, in the county of King and State 5 of Washington, have made a certain new and useful Invention in Heels for Boots and Shoes, and declare the following to be a full, clear, and exact description of the same, such as will enable others skilled in the art 10 to which it appertains to make and use the invention, reference being had to the accompanying drawings, and to letters or figures of reference marked thereon, which form a part of this specification.

15 The invention relates to improvements in shoes, and has particular relation to means for attaching heels thereto.

An object of the present invention is the provision of means for readily and securely 20 attaching the heel to the shoe, said means being further adapted to add to the attractive appearance of the shoe.

Another object of the invention is the provision of a shoe attaching means which 25 includes a plate adapted to be attached to the heel portion of a shoe and having means engageable with the heel, whereby the latter will be securely held in place.

The invention consists in the novel construction and combinations of parts, as hereinafter set forth.

In the accompanying drawings, illustrating the invention:

Figure 1 is a side view of the rear portion of a shoe, illustrating the use of the invention.

Figure 2 is a vertical longitudinal section of the same.

Figure 3 is a bottom plan view of the heel and attaching plate.

Figure 4 is a top plan view of the heel detached from the shoe.

Figure 5 is a plan view of the blank from which the attaching plate is bent.

Figure 6 is a bottom plan view of a modified form of plate.

Figure 7 is a bottom plan view of still another form of plate.

Figure 8 is a top plan view of a heel, adapted for use with the plate shown in Figure 7.

Figure 9 is a vertical longitudinal sectional view through a portion of the shoe and heel, with the plate shown in Figure 7.

Figure 10 is a section through the plate, taken on line 10—10, of Figure 9.

Figure 11 is a view similar to Figure 9, showing a further modification of the plate.

In these drawings the numeral 10 indicates a fragmentary portion of a shoe, to 60 which is attached a heel 11, having a forward projecting upper extension 11^a.

For the purpose of attaching the heel to the shoe the present invention provides a plate 12, which is preferably formed of 65 sheet metal and is shaped to conform to the outline of the top of the heel and is further concavo-convex in section so as to conform to the shape of the upper face of the heel and of the adjacent portion of the 70 shoe.

In Figures 1 to 5 of the drawings the plate is shown as provided with marginal projections, having the form of V-shaped teeth 13, but the particular configuration of 75 these teeth is not essential, and may be varied as desired. The teeth 13 are bent downwardly and inwardly to engage the upper edge of the heel 11, and act to hold the plate and heel together. The plate is further provided with openings 14 for the 80 passage of nails or similar fastening devices to provide means for securing the plate to the heel portion of the shoe. The plate as thus described serves as a connection between the heel and the shoe, and to further insure the positiveness of this connection, the upper face of the heel is provided with a transversely extending loop plate 15, while the plate 12 is provided with a downwardly 85 bent tongue 16 engaging beneath the loop plate. In addition, the plate 12 has a forward extension 17 projecting beyond the breast of the heel, for attachment beneath the instep of the shoe, a downwardly and reversely bent hooked tongue or projection 90 forming a rearward continuation of this extension and extending beneath said extension 11^a of the heel and being designed for attachment thereto. The parts 17 and 100 18 may be perforated for the passage of securing nails or may be attached by other means.

In the form of the invention above described, the plate is first nailed to the sole 105 of the shoe and the heel is then placed in position, with tongue 16 engaging loop plate 15. The teeth 13 are then bent to engage the upper edge of the heel and the tongue 18 nailed to the front face thereof, 110 completing the operation. The teeth 13, appearing upon the outer face of the heel

not only aid in holding the heel in place, but are intended to provide an ornamental finish for the shoe.

In Figure 6 of the drawings the attaching means is shown in the form of a U-shaped plate or member 19' having a marginal flange 20' formed by tooth-like projections similar to the projections 13 previously mentioned. The plate 19' is perforated for the passage of securing nails, and the teeth of the flange 20' are bent downward around the upper edge of the heel, in the manner previously set forth.

In Figures 7 to 10 of the drawings a modified form of the invention is shown, wherein the heel is releasably held by the plate 11' in position upon the shoe, which may thus be worn with a variety of styles of heel, interchangeable to suit the occasion.

For this purpose the body of the plate 11' is made separate from the flange portion 19, a third or locking portion or member 20 serving to connect the forward ends of the U-shaped flange and to continue the same across the front face of the heel. The three parts are secured together by a rivet 21 located at one end of the U-shaped member 19, and the body 11' and flange portion 19 may be joined by one or more additional rivets along the same side of the plate.

The body portion of the plate is pierced at 14' for the passage of securing nails, which are thereby properly located within the margin and out of engagement with the flange 19. The flange portion has an inner rim lying between the sole of the shoe and the body portion of the plate, the outer margin of the flange being bent downwardly and inwardly at 13' to engage the upper edge of the heel and hold the same to the shoe sole. This holding action may be seconded by engagement of a tongue 22, secured at its forward edge to the heel, with the wall of a slot 23 of the plate body.

In engaging or disengaging the heel, the locking member 20 is moved pivotally upon point 21, the catch flange 24 at the free end thereof being forced from engagement with catch end 25 of flange portion 19, and the

wedging contact of the heel will spread the free ends of said flange 19 to allow passage of the broader portion of the heel therebetween, the resiliency of the metal serving to restore the flange to normal position, in which it is held by engagement therewith of the catch flange 24. The same movement of the parts will engage or disengage the tongue 22 with its slot 23.

Figure 11 of the drawings illustrates a construction similar to that shown in Figures 7-10, except that the tongue 22 is dispensed with, and that a catch projection 26 is formed in the locking member of the plate, adapted for releasable engagement with a perforation 27 of the body portion. 65

I claim:

1. Shoe heel attaching means, comprising a plate having means of attachment to the heel portion of a shoe and marginal downwardly bent extensions adapted to grip the sides and rear of the upper edge of the shoe heel, said plate having a forward extension beyond the breast of the heel having means of attachment also to the heel portion of the shoe, and a reversely bent hooked projection extending beneath the forward projecting upper extension of the breast of the shoe heel. 75

2. Shoe heel attaching means, comprising a two-part plate one member of which is of U-form and provided with marginal downwardly bent extensions adapted to grip the sides and rear of the upper edge of the shoe heel, and the other member of which has means of attachment to the heel portion of a shoe and is provided with a forward extension beyond the breast of the heel having also means of attachment to the heel portion of the shoe, and a locking member pivotally engaging one end of the said U-form member and adapted for catch engagement with the other end thereof and having a reversely bent hooked projection extending beneath the forward projecting upper extension of the breast of the shoe heel. 95

In testimony whereof I affix my signature.

CHRISTIAN P. PAULSEN.
